UNITED STATES PATENT OFFICE

147,108

DESIGN FOR A LENS HOUSING

Robert Cadwallader, Detroit, Mich., assignor to
Chrysler Corporation, Highland Park, Mich., a
corporation of Delaware

Application December 29, 1945, Serial No. 125,099

Term of patent 7 years

(Cl. D48—32)

To all whom it may concern:

Be it known that I, Robert Cadwallader, a citizen of the United States, residing at 17580 Pennington Drive, in the city of Detroit, county of Wayne, and State of Michigan, have invented a new, original, and ornamental Design for Lens Housing, of which the following is a specification, reference being had to the accompanying drawing, forming part thereof, in which:

Fig. 1 is a front elevational view of the lens housing showing my new design;

Fig. 2 is a top plan view of the same; and
Fig. 3 is an end elevational view thereof, looking at the left end of Fig. 1.

The characteristic features of my design are shown by the full lines in the drawing.

I claim:

The ornamental design for a lens housing, substantially as shown and described.

ROBERT CADWALLADER.
